UNITED STATES PATENT OFFICE.

JESSE W. RENO, OF NEW YORK, N. Y.

SUBMARINE-DESTROYER.

1,173,463.

Specification of Letters Patent. Patented Feb. 29, 1916.

Application filed July 26, 1915. Serial No. 41,816.

To all whom it may concern:

Be it known that I, JESSE W. RENO, a citizen of the United States of America, and resident of the city, county, and State of 5 New York, have invented certain new and useful Improvements in Submarine-Destroyers, of which the following is a specification.

My invention relates to submarine 10 destroyers.

The object of my invention is to provide a device which is adapted to be held submerged in water through which submarines may be expected to pass and which shall be 15 capable of exploding a bomb in such proximity to the submarine as to destroy the same and which, at the same time, shall be inoperative against ordinary merchant or naval vessels other than submarines, even though 20 such vessels should make contact with said device.

My invention consists in providing a ring of sufficient diameter to permit a submarine to enter the same, in providing a net or 25 other structure which normally hangs across the space and substantially in the plane bounded by said ring, in providing a movable member adapted to carry an explosive bomb in the lower part of said ring, and in 30 providing connections between said movable member and said net whereby when a submarine enters said ring it will engage said net and thereby raise the bomb held in said movable member into contact with the submarine and explode the same.

In the drawings accompanying and forming part of this specification Figures 1 and 2 are front and side views respectively of my invention. Fig. 3 is a detail of the lower 40 part of the ring showing the guard or case in which the explosive bomb is normally positioned.

Numeral 1 represents a ring preferably made of steel tubing which is suspended by 45 the chain 2 from the float 3. Attached to the ring at intervals by means of hooks 5 is the web or net 4 which may be made of wire or Manila rope or chain.

The hooks 5 are made of such strength as 50 to permit their straightening out or breaking when the net is engaged by a submarine. At the sides of the rings I provide vanes 6, preferably made of heavy canvas or other similar material, the purpose of which is to 55 retard the movement of the ring when the net is engaged by a submarine. At the bot-

tom of the ring I provide a sleeve 7 which is secured to the ring and through which passes the spar 8. The lower end of the spar has the ropes 9 secured thereto which ropes pass 60 through the guides 10 and over the pulleys 11 and are secured to the net. At the upper end of the spar a bomb 12 is secured, the bomb being provided with any approved kind of detonator adapted to explode same 65 when the bomb is brought up into contact with the hull of the submarine. The guard 13 is secured to the ring and adapted to surround the bomb and to prevent the displacement or explosion of the bomb in case the 70 ring were contacted in any other manner than by a submarine entering the ring and engaging the net.

The apparatus may be anchored or left 75 free to drift with the current of the water in which it is placed. In the operation of the device, when the bow of the submarine enters the rings it will carry forward the net, the ring itself being retarded by the vanes 6, and in carrying forward the net the 80 spar containing the bomb will be elevated into contact with the bottom of the submarine and thereby explode the bomb and destroy the submarine.

The extreme simplicity and relatively 85 small cost of my submarine destroyer makes it feasible to use them in large numbers without danger to any other type of vessels than submarines which can enter the ring and the moral effect of the presence of these submarine destroyers will retard submarine commanders from entering an area which is 90 protected by them.

Having thus described my invention what I claim is:

1. In a submarine destroyer the combination with a ring and means for supporting said ring in the water, of an explosive bomb secured to said ring and means connected with said bomb and said ring adapted to explode said bomb when a body enters said ring, said means being inoperative by contact with bodies external to said ring.

2. In a submarine destroyer the combination with a ring and a float attached thereto, 105 of movable members attached to said ring and adapted to be engaged by a body entering said ring, a bomb carried by said ring and connections between said bomb and said movable members by means of which said 110 bomb is exploded when a body enters said ring.

3. In a submarine destroyer the combination with a ring and a float attached thereto, of a net secured across the face of said ring, an inwardly movable bomb holder carried by said ring and connections between said holder and said net adapted to move said holder toward the center of said ring.
4. In a submarine destroyer the combination with a ring and a float attached thereto, a net secured to said ring by means of releasable connections, a vertically movable bomb holder attached to said ring and flexible connections between said bomb holder and said net adapted to raise said bomb holder when said net is moved away from the plane of said ring.
5. In a submarine destroyer the combination with a ring provided with vanes adapted to retard its movement in water, of a movable member adapted to be engaged by a body entering said ring, a movable bomb holder mounted on said ring and connec-

tions between said movable member and said movable bomb holder.

6. In a submarine destroyer the combination with a ring and a float attached thereto, of a net suspended in said ring, a vertical guide secured to the lower side of said ring, a spar adapted to move vertically in said guide having a bomb secured to its upper end, a stationary guard secured to said ring adapted to inclose said bomb when said spar is in its lowest position, and connections between said spar and said net whereby the displacement of said net from the plane of said ring elevates said spar.

In testimony whereof, I have signed my name to this specification in the presence of two subscribing witnesses.

JESSE W. RENO.
